WATER-HEATING SYSTEM.

1,020,755.

Specification of Letters Patent. Patented Mar. 19, 1912.

Application filed October 2, 1909. Serial No. 520,629.

To all whom it may concern:

Be it known that I, JOSEPH W. GAMBLE, a citizen of the United States, residing at Philadelphia, in the county of Philadelphia and State of Pennsylvania, have invented certain new and useful Improvements in Water-Heating Systems, of which the following is a specification.

This invention is directed to the provision of an improved system of heating water for use in boilers and heating apparatus.

The invention is directed particularly to the provision of a heating apparatus for use in supplying water to the boilers of locomotives, including feed-water for the boilers of the locomotives and water for washing such boilers, the steam discharged from a boiler when the latter is to be cleaned and refilled being utilized for heating the water which is subsequently to be used as feed-water for the boiler.

The object of the invention is to provide an improved form of heating apparatus, which is reliable, efficient and economical in operation and which may be constructed at comparatively low cost.

In accordance with the invention, a tank is employed in which is stored the heated water which may be used for washing and filling the boilers of locomotives and steam discharged from the boilers of the locomotives is carried into this tank and through the water therein so as to impart its heat to the water. The water within the tank is normally maintained at a substantially uniform temperature, and the means for accomplishing this includes a heater and a circulating system by which water is drawn from the tank, carried through the heater wherein its temperature is raised, and then carried back to the storage-tank. The pump for this circulating system is controlled automatically in response to changes of temperature of the water in the tank; when the temperature of the stored water falls below that which is desired, the circulating pump starts or has its speed increased so as to circulate the water through the heater and thereby bring it up to the desired temperature. In combination with these parts, I preferably employ a supply of live steam which is opened automatically under predetermined conditions, and other devices as hereinafter described.

I have illustrated the preferred embodiment

of my invention in the accompanying drawing, which illustrates diagrammatically the apparatus employed.

Referring to this drawing, 1 indicates the storage-tank, in which is stored the water for washing and filling the boilers of the locomotives. At one end of this tank is a heater 2 having therein a plurality of trays 3, and cold water is admitted to the top of this heater through a pipe 4, this water falling down over the trays 3 while steam is passing upwardly through the heater, so that the temperature of the water is raised by this steam. After passing over the trays, the water drops into a chamber formed by walls 5 and 6 mounted within the tank 1, and passes from the bottom of this chamber into the bottom of the storage-tank 1. At the other end of the tank 1, is a blow-off chamber 7 formed by walls 8 and 9, the former mounted within the tank 1 and the latter constituting the end wall of the tank. To the top of this chamber 7 is connected a blow-off pipe 10, having a check-valve 11 therein, and means are provided for making connection between the pipe 10 and the boilers of the locomotives to be blown off.

In the side of the chamber 7 is an opening leading to a chamber 12 having a suitable float-valve 13 therein, such that when the water rises to a predetermined height within the chamber 7 it will operate the float-valve 13 so as to permit the water to flow off to waste through a pipe 14. A baffle-plate 15 is secured to the side of the chamber 7 over the opening leading to the float-valve 13, and this baffle-plate extends downwardly adjacent to the bottom of the chamber 7, so that the water which passes out through the float-valve 13 is drawn from the bottom of the chamber 7. By reason of the provision of the baffle-plate 15, the water blown off from the locomotive through the pipe 10 settles within the chamber 7 and ample time is allowed for the liberation of the steam contained in the water. This steam rises within the chamber 7 and passes over a wall 16 therein and downwardly through a passageway provided by this wall and the wall 8 of the chamber 7. At the lower end of this passageway connection is made to a pipe 19 extending along the side of the storage-tank 1 near the bottom of the latter. This pipe 19 is provided at a plurality of points along its length with connections 20

for carrying the steam from the pipe 19 into the storage-tank 1. The steam rises through the water within the storage-tank and in doing so imparts its heat to the water. 5 after which such steam as is not condensed passes over the wall 6 into the heater 2, wherein it rises through the series of trays 3 and passes out at the outlet-opening 21. In order to replenish the supply of water in 10 the storage-tank 1, a float 22 is provided within the tank, connected by suitable levers with a valve 23 in the cold water-supply pipe, so that when a predetermined amount of water is drawn from tank 1 the float- 15 valve will be operated to open valve 23 more or less and thus admit water through pipe 4 to the heater 2.

In order to insure the maintenance of a predetermined temperature within the tank 20 1, a circulating system is provided, by which water is circulated from the bottom of tank 1 through the heater 2 and back into the tank, and this circulating system is automatically controlled, so that it will be 25 brought into operation whenever the temperature of the water in tank 1 falls below that desired. This circulating system includes a pump 24 connected by pipe 25 to the bottom of the tank 1 and by pipe 26 with 30 the top of the heater 2. Steam for operating the circulating pump 24 is admitted to the pump through a pipe 27, and the admission of this steam is automatically controlled by a valve 28 operated by a thermostat 29 35 which is mounted upon the side of the tank 1 and is responsive to changes of temperature of the water within that tank. When the temperature of the water in tank 1 falls, the thermostat operates to open the valve 40 28 and thus admit more steam to the pump 24, and the latter causes circulation of the water from tank 1 through the heater 2. When the temperature of the water in tank 1 has been raised to that desired, the thermostat 45 will operate to move valve 28 toward the closed position, but preferably the valve will not be entirely closed but will permit of the supply of enough steam to pump 24 to keep the pump operating slowly.

50 It may be that at times the steam rising through the water in tank 1 and passing up through the heater 2 would not be sufficient to maintain the temperature desired for the water within tank 1, and I have 55 therefore provided a live-steam connection, whereby steam from a source of supply other than the locomotive which is blown off through pipe 10 may be automatically admitted to the chamber 7 and from that 60 chamber to the tank 1 and heater 2. This live-steam connection is shown at 30 and has a diaphragm-valve 31 connected therein. This diaphragm-valve is connected by the pipe 32 to the pipe 33, which connects 65 the thermostat 29 with the valve 28, and if

the temperature of the water in tank 1 is not raised to the desired point by the heater 2, employing the steam blown off from the locomotive, the further operation of the thermostat 29 will cause the diaphragm-valve 31 to open and admit live-steam through the pipe 30 to the chamber 7 and from the latter to the tank 1 and heater 2. 70

Water for washing the locomotive-boilers is pumped from the tank 1 through a pipe 34 connected to the upper portion of the tank 1 by a pump 35 forcing the water through a pipe 36 to the locomotive. 75

Between the wall 5 within the tank 1 and the end wall of the tank, is a second heater 37 having trays 38 therein. Water is supplied to the top of this heater by a pipe 39 connecting with the cold-water-supply pipe 4, and in this pipe is a valve 40 operated by a float 41 within the heater 37. 80 Steam is led to the trays 38 within the heater 37 through a pipe 42 connected with the exhaust of stationary steam-engines within the plant and any other apparatus exhausting steam. This steam passes upwardly around the trays 38 so as to heat the water falling over these trays, and if more steam is entering through the pipe 42 than is required for heating the water within the heater 37 this excess of steam passes through 85 an opening in the wall 5 and upwardly about the trays 3 of the heater 2 and then out through the pipe 21. The water collecting at the bottom of the heater 37 may be used for filling the boilers of the stationary engines about the plant, this water being drawn off by a pump 43. The water-chamber within the heater 37 and the tank 1 are provided with suitable drain-cocks 44. 90

In employing the apparatus above described, the method of operation may be substantially as follows: The water within tank 1 is normally maintained at a temperature such that it is suitable for use as washing water in cleaning the boilers of locomotives. For this purpose, the water is pumped through the pipe 34 by the pump 35. The maintenance of this temperature is effected by the circulation of the water from the tank 1 through the heater 2 and then back to the tank, the water being heated within the heater by steam rising from the water in tank 1 and by the excess of steam entering through pipe 42 over that required in the heater 37. Cold water is supplied to the tank 1 through the heater by the pipe 4 when the valve 23 in that pipe is opened by the float 22. This circulation of the water from tank 1 through the heater 2 is automatically effected by the pump 24 controlled 115 by the thermostat 29, the pump being started or being brought up to normal speed whenever the temperature of the water in tank 1 falls enough to cause the thermostat to operate the valve 28. If the temperature 120

of the water within tank 1 falls below a predetermined amount, this is due to the fact that the steam passing through the heater 2 has been insufficient to impart the required heat to the water which is being circulated by the pump 24, and the thermostat 29 then operates the diaphragm-valve 31 so as to admit live-steam through the pipe 30 to the chamber 7, and this steam 5 passing through the water in tank 1 and upwardly through the heater quickly brings the water in the tank 1 up to the required temperature. When a boiler is to be blown off, suitable connection is made to the pipe 10, and when the water and the steam in 15 the boiler are delivered into the chamber 7, the water flows out from the bottom of the chamber to waste, but the steam rising from the water is carried into tank 1, in which it 20 passes upwardly through the water therein to the heater 2.

Having described my invention, what I claim as new therein and desire to secure by Letters Patent of the United States is:

25 1. In a system for supplying water to locomotive boilers, the combination of a water storage tank, means for supplying water thereto, a heater, means for carrying steam blown off from a boiler to the heater, means 30 for circulating water from said tank through the heater, means for automatically controlling said water circulation in accordance with changes of temperature of the water in said tank, and means for supplying water 35 from said tank to the locomotive boiler, substantially as set forth.

2. In a system for supplying water to locomotive boilers, the combination of a water storage tank, means for supplying water 40 thereto, means for carrying steam blown-off from a locomotive to the tank, a heater having a series of trays therein and a water chamber below said trays, a steam connection from the upper portion of said tank to 45 said heater, a connection from the water chamber of said heater to said tank, a pump, connections to said pump for drawing water from the lower portion of said tank and carrying it to the trays of the heater, means for 50 automatically controlling the operation of said pump in accordance with changes of temperature of the water in the tank, and means for supplying water from said tank to the locomotive boiler, substantially as set 55 forth.

3. In a system for supplying water to locomotive boilers, the combination of a water storage tank, a heater having a series 60 of trays therein and a water chamber below said trays, a steam connection from the upper portion of said tank to said heater, a connection from the water chamber of said heater to said tank, a pump, connections to said pump for drawing water from the lower 65 portion of said tank and carrying it to said

trays of the heater, a thermostat extending within said tank and controlling the operation of said pump, a pipe for carrying water to said trays of the heater, a valve in said pipe, a float in said tank operating said valve, means for supplying water from said tank to a boiler, and means for supplying steam to said tank, substantially as set forth.

4. In a system for supplying water to locomotive boilers, the combination of a tank, 75 a heater, a blow-off chamber, means for discharging the contents of a boiler into said chamber, a pipe for carrying steam from said chamber to the lower portion of said tank, means for carrying steam from the upper portion of said tank to said heater, means for circulating water from said tank through said heater, means for automatically controlling said circulation in accordance with changes of temperature of the water in 80 said tank, and means for supplying water to a boiler from said tank, substantially as set forth.

5. In a system for supplying water to locomotive boilers, the combination of a tank, 90 a blow-off chamber, means for connecting said chamber to a locomotive, a steam connection from the upper portion of said chamber to the lower portion of said tank, a heater having a plurality of trays therein 95 and a water chamber below said trays, a steam connection between the upper portion of said tank and said heater, a water connection between said water chamber and the tank, a pump, connections to said pump for 100 circulating water from said tank through said heater, a water supply pipe connected to said heater, a thermostat within said tank and controlling the operation of said pump, and means for supplying water from said 105 tank to a boiler, substantially as set forth.

6. In a system for supplying water to locomotive boilers, the combination of a water storage tank, a heater, means for circulating water from said tank through said heater, 110 means for automatically controlling said water circulation in accordance with changes of temperature of the water in said tank, means for supplying steam blown off from a locomotive boiler to said tank, a second 115 source of supply of steam connected to said tank, means for automatically admitting steam to the tank from said second source under predetermined conditions and means for supplying water from said tank to the 120 locomotive boiler, substantially as set forth.

7. In a system for supplying water to locomotive boilers, the combination of a water storage tank, a heater, means for circulating water from said tank through said heater, 125 means for automatically controlling said water circulation in accordance with changes of temperature of the water in said tank, means for supplying steam blown off from a locomotive boiler to said tank, a second 130

- source of supply of steam connected to said tank, means for regulating the supply of steam from said second means also controlled by said automatic controlling means, and 5 means for supplying water from said tank to the locomotive boiler, substantially as set forth.
8. In a system for supplying water to locomotive boilers, the combination of a water storage tank, a heater having a series of trays therein and a water chamber below said trays, a steam connection from the upper portion of said tank to said heater, a connection from the water chamber of said 10 heater to said tank, a pump, connections to said pump for drawing water from the lower portion of said tank and carrying it to said trays of the heater, a thermostat extending within said tank, means operated thereby for controlling the operation of 15 said pump, means for supplying steam blown off from a locomotive boiler to said tank, a second source of supply of steam to said tank, means operated by said thermostat for controlling said second source of supply of steam, and means for supplying water from said tank to the locomotive 20 boiler, substantially as set forth.
9. In a system for supplying water to locomotive boilers, the combination of a tank, a wall within said tank dividing the same into a water-receiving chamber and a storage chamber, a plurality of trays mounted within the tank over said receiving chamber, a passageway through said wall near the top thereof for steam from the storage chamber to the trays, a passageway through said wall near the bottom thereof for water from the receiving to the storage chamber, 25 means for circulating water from the storage tank to said trays, means for supplying steam blown off from a locomotive boiler 30
- to said storage chamber, and means for supplying water from the storage chamber to the locomotive boiler, substantially as set forth.
10. In a system for supplying water to locomotive boilers, the combination of a tank having a wall therein dividing the tank into a blow-off chamber and a storage chamber, a pipe for connecting the locomotive boiler to the blow-off chamber, a steam connection from the upper portion of the blow-off chamber to the lower portion of the storage chamber, a heater connected to the upper portion of the storage chamber, means for supplying water to the heater, and means for supplying water from the storage chamber to the locomotive boiler, substantially as set forth.
11. The combination of a tank having three walls therein dividing the tank into a blow-off chamber, a storage chamber and two water-receiving chambers, a set of trays mounted within the tank above each of said receiving chambers, means for supplying water to said trays, a pipe connected to said blow-off chamber, a pipe connecting the upper portion of the blow-off chamber with the lower portion of the storage chamber, a steam connection to one of said sets of trays from the upper portion of the storage chamber, a connection from the receiving chamber of said set of trays to the storage chamber, a pipe for carrying steam to the other of said sets of trays, and a steam connection from one of said sets of trays to the other, substantially as set forth.

This specification signed and witnessed this 30th day of September, 1909.
